[57] CLAIM

The ornamental design for a can retriever, as shown and described.

DESCRIPTION

FIG. 1 is a front elevational view of the can retriever showing my new design;

FIG. 2 is a side elevational view;

FIG. 3 is a back elevational view;

FIG. 4 is a top elevational view; and

FIG. 5 is a bottom elevational view.

The handle has been shown broken away in FIGS. 1-3 to indicate indeterminate length.
